MODELING CLAY PACKAGE

Ruth T. Heineman, Norwood, and John F. Miller,
Deer Park, Ohio; said Miller assignor to said
Heineman

Application April 19, 1947, Serial No. 742,690

4 Claims. (Cl. 206—46)

1

This invention relates to a package for deformable material and particularly to material of this nature bearing an impression, which it is desired to preserve.

One of us, for a number of years, made small plaques or tiles of porcelain bisque bearing a child's hand print. Parents of small children often desire to preserve for themselves, or for the child's later life, mementoes of the child's babyhood, and a hand print of a small child, suitably preserved in a colorful tile or a plaque, is a very desirable childhood memento.

In the past the procedure has been to prepare a slab of suitable clay and call at the residence of the subject and take an impression of the child's hand. The slab of clay was then taken home and suitably fired and tinted, and it was then returned to the purchaser in its finished form. These tiles or plaques have been sold under the registered trade-mark "Pattyprint."

Production with the procedure outlined above is relatively slow and quantity is distinctly limited. We have determined that production may be greatly increased if a suitable clay could be marketed in a suitable container through infant departments of leading department stores. In this way the parents or other relative of the child in question could purchase a package containing a suitable clay and could take the imprint of the child's hand at home. Then, the entire package could be mailed to our plant, where we could complete the processing and ship the completed tile or plaque back to the original purchaser.

In connection with the provision of such a package, a number of problems arise among which are that a suitable clay must be provided which will remain plastic for long periods of time. This particular problem forms no part of the present invention and will not be discussed further. It is also necessary to provide means whereby the clay slab, bearing the impression can be readily removed from the container. It is also necessary to provide a construction whereby the impression in the clay surface will be preserved from damage or deformation, which might result from rough handling during shipment, or from contact with the lid.

Our objects include the solution of the problems discussed above as well as others, which will be explained in more detail hereinafter, or which will be apparent to one skilled in the art upon reading these specifications.

Reference is made to the drawings forming a part hereof and in which:

2

Fig. 1 is a plan view of a package according to our invention.

Fig. 2 is a diametral cross sectional view taken on the line 2—2 of Fig. 1.

Fig. 3 is a view similar to Fig. 2, but showing the package in the form in which it will be sold.

Briefly in the practice of our invention we provide a container which is of a relatively rigid material, preferably sheet metal, and which may be in plan of a size and shape suitable for a plaque to bear the imprint of a child's hand. We provide a liner for the container which is of a material which will not adhere to the container, so that the body of deformable matter contained in the container may easily be removed by us for further processing. We provide our container with a cover or lid, which may be of the slip-on type, but which is preferably of screw type if the container is circular, and we provide means for spacing the cover above the top surface of the material contained therein.

The container body is indicated generally at 10 in the figures and according to our preferred form is circular, whereby we achieve a circular tile or plaque. The circular form also enables us to provide a screw lid which we prefer. It will also be understood that the container could be square, rectangular, or of any other desired shape.

The container is provided with a liner, which according to our preferred embodiment comprises a circular bottom disk 11 and an annular ring 12 of a material which will not adhere to the sheet metal container body. We prefer to use as a material for the liner an oil treated boxboard, and while the thickness of the member 12 is not of particular importance, the bottom disk 11 should be thick enough to sustain the weight of the body of deformable material 13 with which the container is filled.

As seen in Fig. 3, we cover the body of deformable material 13 with a sheet 14 of protective material, which may be oil treated boxboard, or preferably metal foil. Thus in the package of Fig. 3, the material 13 is substantially sealed against the atmosphere by moisture proof material, so that the deformable material would not tend to dry out as a result of standing for long periods of time.

The lid 15 of the container, which as indicated above preferably has threaded engagement with the container body as at 16, is provided on its underside with an annular gasket 17 which seats on the protective sheet 14 and is supported by the annular member 12. Thus when the lid 15

is tightly screwed on to the body 10, the package in cross section has the appearance of Fig. 3. The spacing between the cover 15 and the protective sheet 14 prevents the surface 13a of the deformable material from being damaged.

The purchaser having acquired the package of Figs. 3 will remove the lid 15 to which the gasket 17 may be adhesively secured and will peel off the protective sheet 14. The child's hand will then be pressed into the deformable material 14 to make the impression 18, which it is desired to preserve.

The protective sheet 14 will be discarded and the lid 15 will again be screwed down tightly at which time the package will have the appearance in cross section, shown in Fig. 2. In this condition the package will be shipped back to us for further processing and again the spacing between the member 15 and the surface 13a of the body of material 13 will prevent damage to the impression 18, which might result from rough handling in shipment, or from contact with the lid.

As will be seen from the foregoing description, our invention has three aspects. We have provided a container for a particular purpose; we have provided a package containing a deformable material in an undeformed state; and we have provided a package containing a deformable substance, bearing an impression on its top surface which is to be preserved.

The composition of the deformable material, the procedures for preparing the same, and the procedures in connection with coloring and firing the plaque after the impression has been obtained form no part of the present invention.

It will be clear that various modifications may be made in our precise package without departing from the spirit of our invention, and we therefore do not intend to limit ourselves, except as pointed out in the claims which follow.

Having now fully described our invention what we claim as new and desire to secure by Letters Patent is:

1. As an article of manufacture, a container, a stiff bottom lining piece snugly fitting in the bottom of said container, a lining collar in said container resting on said bottom lining piece, said lining piece and collar being of a material which will not adhere to said container, a body

of modeling clay in deformable condition in said container supported on said bottom lining piece and snugly embraced by said lining collar, and a lid for said container, said lid having an annular spacing collar which, in the assembled condition of said article, bears upon said lining collar and peripherally on said body of modeling clay.

2. An article of manufacture according to claim 1 in which said container and lid have threaded engagement.

3. An article of manufacture according to claim 1 in which said lining piece and collar are of moisture-proof material.

4. An article of manufacture according to claim 1 wherein said lining piece and collar are of moisture-proof material and wherein there is provided a cover sheet of moisture-proof material of a size and shape to fit snugly within said container covering said body of modeling clay and said lining collar so that in the assembled condition of the article the cover sheet is engaged between said lining collar and said spacing collar.
